UNITED STATES PATENT OFFICE.

JAMES B. KINGAN, OF SCHENECTADY, NEW YORK.

CROSS-HEAD.

No. 830,080.

Specification of Letters Patent.

Patented Sept. 4, 1906.

Application filed April 5, 1905. Serial No. 254,057.

To all whom it may concern:

Be it known that I, JAMES B. KINGAN, a citizen of the United States, residing at Schenectady, in the county of Schenectady and 5 State of New York, have invented certain new and useful Improvements in Cross-Heads and Piston-Rods of Reciprocating Engines, of which the following is a specification.

This invention relates to cross-heads and piston-rods combined of reciprocating engines, and especially to those employed in locomotive-engines.

The object of this invention is to provide a 15 piston-rod and cross-head so combined in a single piece as to be durable and less expensive to repair and which will avoid the inconvenience incident to breakage at the keyway of the piston-rod or the screw-threaded portion of same sometimes employed for securing the piston-rod to the cross-head.

It consists in a piston-rod provided at its rear end with a cross-head made integral with the same by forging or welding and with provision for receiving upper and lower wearing-shoes for coaction with guide-rods for guiding the movements of the cross-head and piston-rod. The cross-head when complete may be of the same general form and 25 dimensions as cross-heads now in general use and has the advantage and features of great permanency, while the line of union of the cross-head with the piston-rod is strengthened by an annular cove to obviate a breakage of the piston-rod outside of the cross-head, which is now a common occurrence.

Other purposes and advantages of this invention will be clearly shown and set forth in the specification, when taken in connection 35 with the accompanying sheet of drawings, in which—

Figure 1 is a plan view of the piston-rod and cross-head complete and connected with the piston-head in the manner usually practiced by the trade. Fig. 2 is a side elevation of the same. Fig. 3 is a view of the rear end of the cross-head. Fig. 4 is a side elevation of the cross-head prior to being furnished with the wearing-shoes and shows it and the 45 piston-rod to be made integral. Fig. 5 is a plan view of the same. Fig. 6 is a front end view of the cross-head. Fig. 7 is a rear end view of the same. Fig. 8 is an end view of one of the cross-head wearing-shoes. Fig. 9 55 is a side view of the same. Fig. 10 is a plan view of the same. Fig. 11 is a side elevation

showing a modification of the cross-head and shows one of the shoes applied. Fig. 12 is a side view of a wearing-shoe, illustrating another method of constructing the same. 60 Fig. 13 is a section of a wearing-shoe taken at line 1 in Fig. 12. Fig. 14 is a section of a wearing-shoe taken at line 2 in Fig. 11.

The same letters of reference refer to similar parts throughout the several views. 65

In the drawings, A, Figs. 1, 2, 4, 5, and 11, is a single piece of metal consisting of piston-rod A' and cross-head B, made integral by forging or welding. At the line of union of the piston-rod and cross-head is provided a 70 circular cove a (shown in the same figures) for strengthening the metal at this point and also avoiding the occurrence of a shoulder, where breakage usually occurs. The cross-head B is made with solid portion C and has 75 made integral with said solid portion the cheeks or jaws C', which are provided with the wrist-pin opening C². Between these jaws is the opening D, Figs. 1, 5, and 7, in which works the end of a connecting-rod, 80 (not shown,) which is connected in the usual manner to a wrist-pin (not shown) inserted in wrist-pin opening c². The forward ends of jaws c' act as flanges for holding the wearing-shoe E and are provided with bolt-holes 85 e, as shown in Fig. 4, and indicated by dotted lines in Figs. 5, 6, and 7, which coincide with other bolt-holes f, made in the forward end of wearing-shoe E.

The wearing-shoe, Figs. 8, 9, and 10, preferably made of steel, consists of the body portion E, carrying on one of its surfaces the longitudinal flanges e² e², producing the way e', in which the usual piston-guide rods (not shown) work, and on the opposite surface is 95 the tongue F. This tongue F is provided at its forward end with bolt-holes f f, which when the shoe is in place, as shown in Figs. 1 and 2, coincide with the bolt-holes e in the cross-head B and form a continuous passage 100 for the bolts G for securely clamping and securing said wearing-shoes to the cross-head, the tongue F of the wearing-shoe acting as a steadiement to same between the jaws c' of the cross-head B. The bolts G are provided 105 with countersunk heads at the inside of the cross-head, as is usual with the trade, and are threaded at their outer ends and provide with nuts, as shown in Figs. 1, 2, 3, and 11.

Fig. 11 shows a modification of this cross-head and its shoe. This cross-head is constructed similar to that shown in Figs. 4 and

5, excepting that the solid portion *c* extends from top to bottom of the same, and there is provided in its forward end the recesses *H* for engagement with the wearing - shoe. 5 Bolt-holes *h* are also provided, as shown. The wearing-shoe *E'*, Figs. 11 and 14, is of the same general form as shown in Figs. 8, 9, and 10, excepting that the tongue *F'* is made of reduced depth and the sides at their forward ends have flanges *h'*, which exactly fit the recesses *H* of the cross-head, and they are provided with bolt-holes corresponding with the bolt-holes in the cross-head when the shoe *E'* is in place, which receive bolts 10 made as before described and are clamped and secured by means of the nuts on the threaded end of said bolts.

Figs. 12 and 13 illustrate another method of constructing the wearing-shoe. In this 20 shoe the body *E''* may be made of cast-iron, bronze, or other suitable material or alloy and is provided with the usual guide-flanges *e''* and the shallow tongue *F'*. The sides *J*, provided with flanges *j* for engagement with the recesses *H*, Fig. 11, are rabbeted into the body *F''* of the wearing-shoe and are secured to the same by means of transverse bolts *G'*, as shown in Figs. 12 and 13. Bolt-holes are also provided in flanges *j*, which will coincide 25 with bolt-holes *h*, Fig. 11, when the wearing-shoe is in place on cross-head, and the two are secured together by the bolts *G*, made as described and in the manner above set forth.

30 It is to be understood that while the cylinder in which the piston above referred to works and also the stuffing-box, with its glands and piston-rod packing used in this class of engines, are not shown, it is necessary 35 to provide a proper stuffing-box and also means for the passage of the cross-head through the cylinder from front to rear. It is also evident that this could not be done and still use the stuffing-box with the rear 40 cylinder-head constructed in the usual way. but I attain my object by making a circular opening in the rear cylinder-head of a diameter equal to the diagonal diameter of the cross-head *B*, which is indicated by broken 45 line *X* in Fig. 6, and I provide a peculiar and novel construction of stuffing-box which is subject-matter for another application for 50 patent and cannot be shown in this application.

55 The manner in which this cross-head made integral with the piston-rod is applied for proper operation in a reciprocating engine is as follows: The piston-head *P*, which is constructed as usual and provided with packing- 60 rings *P*, is secured to the forward end of the piston-rod in the preferred manner practiced by the trade. The forward cylinder-head being removed, the cross-head is inserted and passed through the cylinder rearward. Then 65 it is passed through the opening in the back

cylinder-head (indicated by broken line *X*, Fig. 6) and into its place between the guide-rods, when the upper and lower wearing-shoe *E* will be applied and the bolts *G* inserted and passed through both wearing-shoe and cross-head and secured by the nuts *g*, all as above described. Then the stuffing-box, with its piston-rod packing, which will be of a construction suitable for its purpose and applicable to this invention, will be placed in position and secured to the rear cylinder-head. A chamfer *Y* at each of the corners of the cross-head *B*, Figs. 4 and 6, may be used to advantage sometimes, as it will allow the opening *X* in the back cylinder-head to be 80 made smaller and still pass the cross-head through same.

The advantages I claim for my invention over the old method of constructing cross-heads, especially for locomotive-engines, may 85 be understood, as it is well known that the different kinds of piston-rods now in common use on locomotives have caused great trouble due to breakage at the keyway in the cross-head fit, where keys are used, or in the 90 threaded part of the piston-rod where the same is secured to the cross-head by means of nuts. This trouble is not due to the stress or strain exerted by the steam working against the piston, but to the great strain 95 exerted on the piston-rod by driving the taper-key in the one case or by drawing the nuts up sufficiently tight to insure the rod against working loose in the cross-head in the other case. In either case the rod must be 100 drawn into the taper fit of the cross-head to a tension exceeding the force exerted by the steam-pressure against the piston, which tension is more than the metal of which the piston - rod is made will stand, hence the 105 breakage, resulting in engine failures, delays, and in many cases excessive damage to the other parts of the engine.

Having described my invention, what I claim, and desire to secure by Letters Patent, 110 is—

A device constructed for service in a reciprocating engine, the combination in a single piece, of a piston-rod portion and a cross-head portion made integral by forging or 115 welding, the cross-head of a piece comprising the solid portion *c*, opening *D* between the jaws for receiving the end of a connecting-rod, a portion of which jaws serve as flanges to receive wearing-shoes, and a circular cove *a* at 120 the line of union of the piston-rod with the said cross-head for strengthening the metal of said piece at said line of union, the rear end portion of the piston-rod being made to secure the said piece to the piston.

JAMES B. KINGAN.
